SWITCH-SOCKET FOR ELECTRIC LAMP

Louis Ludwig, Brooklyn, N. Y.

Application September 29, 1949, Serial No. 5,220

Term of patent 14 years

(CL. D26—13)

To all whom it may concern:

Be it known that I, Louis Ludwig, a citizen of the United States, residing in Brooklyn, in the county of Kings, State of New York, have invented a new, original, and ornamental Design for Switch-Socket for Electric Lamp, of which the following is a specification, reference being had to the accompanying drawing, forming a part thereof, in which:

Fig. 1 is a side elevational view of a switch-socket for electric lamp showing my new design;

Fig. 2 is a top plan view thereof;

Fig. 3 is an end elevational view showing the prongs which are to be inserted into a receptacle, and

Fig. 4 is an elevational view of the opposite end where a lamp is inserted into the socket.

The dotted lines shown in the drawing are for illustrative purposes only.

I claim:

The ornamental design for a switch-socket for electric lamp, as shown and described.

LOUIS LUDWIG.
